CLAIM

The ornamental design for an enclosure for a computer, as shown and described.

DESCRIPTION

FIG. 1 is a slightly reduced front top and right side perspective view of an enclosure for a computer showing my new design;

FIG. 2 is a top plan view thereof;

FIG. 3 is a bottom plan view thereof;

FIG. 4 is a right side elevational view thereof;

FIG. 5 is a left side elevational view thereof;

FIG. 6 is a front elevational view thereof;

FIG. 7 is a rear elevational view thereof; and,

FIG. 8 is a slightly reduced front top and right side perspective view of a second embodiment thereof wherein the only difference is in the front panel.

FIG. 2

FIG. 4

FIG. 5
